UNITED STATES PATENT OFFICE.

GEORGE E. YEAGER, OF CHICAGO, ILLINOIS.

BURGLAR AND HOLDUP ALARM.

1,193,656.

Specification of Letters Patent. Patented Aug. 8, 1916.

Application filed September 26, 1913. Serial No. 52,551.

To all whom it may concern:

Be it known that I, GEORGE E. YEAGER, a citizen of the United States, and a resident of the city of Chicago, county of Cook, and State of Illinois, have invented certain new and useful Improvements in Burglar and Holdup Alarms, of which the following is a specification.

My invention relates to an electrically operated alarm adapted to be placed in places of business or residences for the purpose of both sounding an alarm and frightening or deterring the marauders, or to be sounded when the building after being closed is entered by unauthorized persons.

One of the objects of my invention is the provision of an alarm apparatus that is tamper-proof, that is, it may not be put out of operation by a burglar without first sounding the alarm, and which requires the services of at least two persons familiar with its operation to inspect the same without attracting attention.

Another object of my invention is to provide an alarm that will automatically detonate several times when set off, so as to frighten the burglar and give the impression that he is being fired at with a revolver, and at the same time to attract the attention of a patrolman or other watchman.

Other objects are the provision of a burglar alarm that is effective in operation, will not readily get out of order, is comparatively inexpensive to manufacture, and capable of operation at all times after loading and adjusting.

I prefer to accomplish the divers objects of my invention by the means and in the manner hereinafter fully described and as more particularly pointed out in the claims, reference being had to the accompanying drawings, forming a part of this specification, wherein,

Figure 1 is a top plan, partially in section, of my alarm removed from its enclosing box or cabinet. Fig. 2 is a front elevation thereof. Fig. 3 is a transverse vertical section taken on line 3—3, Fig. 1, looking in the direction of the arrows and showing the apparatus in position to fire. Fig. 4 is a diagrammatic view of the wiring or circuits employed in my device.

Referring to the drawings, 10 indicates a suitable rectangular shaped box or cabinet made of wood or metal and the bottom wall 11 whereof is hinged by a concealed butt-

hinge 12 so that it may be swung downwardly a proper distance (as illustrated in Fig. 3) for the purpose of firing and sounding the alarm. A suitable chain 13 and spring 14 limits and cushions the drop of the bottom wall 11 so that the same will not fall to a vertical position and cause the charring of the wall of the room in which the apparatus is mounted, by the explosions.

Mounted upon the bottom wall 11 is a suitable solenoid 15, the core 16 whereof extends a suitable distance therefrom so that its outer movable end forms the bolt 17 of a suitable latch by entering a recess 18 made in the adjacent axially alining portion of the front wall of the cabinet 10. The extended end 17 of this core is preferably journaled in suitable bearings 19, 19, one disposed adjacent the solenoid and the other near the outer or front edge of the bottom wall. Owing to the weight of the mechanism and devices mounted upon the bottom wall, I have found it desirable to employ a comparatively weak solenoid 15 so that in the event the switch 20 or push button is manipulated, the strength of the solenoid will be insufficient to overcome the friction caused by said weight on the outer end of the bolt 17, and the latter will not be retracted. However, should a person raise the outer portion of the wall slightly (see dotted lines Fig. 3) the bolt may be retracted by another person operating the switch 20, which latter is preferably located at a considerable distance from the alarm apparatus so that the cabinet cannot be opened by one person.

In a convenient position, preferably adjacent one end of the bottom wall, a rectangular-shaped trigger-plate 21 is mounted, which is bored horizontally to provide a plurality of hammer openings (in this instance five in number, although any desired number may be employed) and into each of which a metal tube 22 is tapped. These tubes are closed at their outer ends by suitable caps 23, having central openings that afford guides or journals for the shanks of reciprocable, spring-actuated plungers 24 and the outer ends of said plungers are hooked or provided with suitable loops 25, through which a transverse bar or rod 26 may be inserted when the plungers are being retracted for the purpose of "setting" the device. The inner ends of plungers 24 are provided with heads 27, having pins 28

extended axially from their end faces opposite said plungers. Pins 28 comprise the firing-pins for discharging the blank cartridges 29 or detonating caps that are 5 mounted in suitable chambers 30, provided in a chamber bar 31 bolted to the front of the plate 21 in alignment with the respective tubes 22. Suitable coiled expansion springs 32 surround the plungers 24 between the 10 caps 23 and heads 27, and in order to insure the guidance of the firing-pins to the cartridges, the inner ends of tubes 22 are closed by plugs 33 having central openings 34 therein for the reception of said firing- 15 pins.

At the rear of the plate 21 the tubes 22 have transverse slots 35 cut in their upper segments, that are of a sufficient width to permit of the insertion of the lower edge 20 of a trigger-blade 36, and when said plungers 24 have been pulled out to their fullest extent, this blade 36 is moved downward into the slots 35, whereupon the plungers 24 may be released and the heads 27 will press 25 against said blade and be held in a retracted position. One end of the blade 36 is pivoted at 37 to the rear surface of plate 21 and its opposite end rests upon or is disposed adjacent a cam or rotatable block 38 secured 30 upon the key spindle 39 of a suitable clock-work (not shown) within a case 40 mounted adjacent the end of the bottom wall 11 opposite the firing elements. The clockwork is of ordinary construction and need not be 35 described except to state that it is provided with an alarm-bell 41 and a substantially L-shaped lever 42 is secured to and movable with the spindle of the escapement pawl. The shorter arm of this lever 42 extends 40 through an opening in the wall of case 40, while the longer arm extends down outside the case 40 and is engaged by an angular shaped spring 43 that exerts its tension to keep the longer arm in a substantially ver- 45 tical plane where the escapement of the clockwork would release the mechanism thereof and permit the same to operate, thereby ringing the alarm bell 41. Under normal conditions this lever is retained in 50 the position illustrated in Fig. 2 of the drawings by means of a pin 44, extending from the outer end of the movable core 45 of a solenoid 46. Interposed in the circuit in which this solenoid 46 is connected are 55 one or more switches 47 that may be located upon the windows, doors and other entrances or exits of the building and also upon counters, cashiers' desks, and the like, so that the closing of the circuit will ener- 60 gize the solenoid 46, thereby retracting its core 45 and causing the lever 42 to return to its normal vertical position and release the escapement of the clockwork. The alarm bell 41 will immediately begin ringing and 65 the winding key spindle 39 will rotate the

block 38, which in turn lifts the free, movable end of the blade 36 so that the plungers are successively released and the cartridges discharged in sequence.

I have found it to be desirable to release 70 and lower the bottom-wall during the sounding of the alarm bell and the firing of the cartridges, and for this purpose it is necessary to release the latch bolt 17 heretofore mentioned, by other means than its respective solenoid 15. I prefer to fulcrum a lever 75 48 so that it is movable in a horizontal plane substantially parallel with the plane of the axis of the latch bolt 17, and the bolt is either slotted or has a portion of its under- 80 side cut away to provide a shoulder 49 adapted to be engaged by said lever when the latter is moved on its pivot in the direction of the solenoid. A comparatively strong contracting spring 50 is connected to 85 the movable or free end of lever 48, in order to keep the latter normally pressed toward the solenoid, and when said spring is permitted to exert its force, the lever will be moved against the shoulder 49 and retract 90 the latch bolt a distance sufficient to release the same. A light gage wire spring 51 engages the outer end of the latch bolt so that under ordinary conditions this spring will force the bolt outwardly and keep the 95 same in engagement with the front wall of the casing. In order to retain the lever 48 in "set" position, that is, when the apparatus is adjusted so as to sound the alarm and fire the cartridges, I provide a suitable L-shaped lever 52 that is fulcrumed intermediate its ends upon the side wall of the clock case 40, so that one end will be disposed in front of and arrest the movement of the lever 48. The lateral member 53 of this lever 100 projects outwardly toward and into the path of the cam block 38, and when the latter is rotated in sounding an alarm, said block 105 will operate said lever so that the end thereof in front of the lever 48 will be raised, thereby releasing the lever 48 and unlocking the latch to permit the bottom wall to open or drop downward as shown in Fig. 3 of the drawings.

For the purpose of concealing the wires, I 115 prefer to mount the alarm device in the angle formed by the ceiling and wall of a room, store or other structure it is desired to protect, and it will be obvious that, when one of the switches 47 is operated to close the 120 circuit therethrough, solenoid 46 will instantly be energized and retract its core 45 which is normally held at the limit of its outward movement by a wire spring 54, thus releasing lever 42, which in turn operates the escapement to start the clockwork. The bell alarm will ring and the rotation of the spindle 39 and block 38 will depress the adjacent end of lever 52 sufficiently to release the end of lever 48 engaged by its opposite 125 130

end, causing the retraction of the bolt 17 and the release of the latch; at the same time the block will raise the adjacent end of blade 36 so that the firing plungers 24 will be released, one by one, to discharge the cartridges.

While I have herein illustrated and described certain instrumentalities for carrying out my invention, it will be obvious to others skilled in the art to which it pertains, that numerous modifications and refinements thereof are possible without materially departing from the spirit of my invention. I therefore desire it understood that all of such changes are contemplated within the scope of my invention as expressed in the appended claims.

What I claim is:—

1. A burglar alarm comprising a plurality of cartridge-holding chambers and means for successively firing the same comprising a corresponding number of firing pins, retractable plungers on which said pins are mounted, a blade movable in front of said plungers adapted to retain the same in retracted position, and devices for moving said blade away from said plungers whereby the latter are released in succession.

2. A burglar alarm comprising detonating elements including a plurality of retractable plungers provided with firing pins, and means controlling said plungers adapted to successively release the same consisting of a pivoted element movable transversely of and in front of said plungers, and a movable device adapted to move said element out of the path of said plungers.

3. A burglar alarm comprising detonating elements including a plurality of retractable plungers provided with firing pins, and means controlling said plungers adapted to successively release the same consisting of a pivoted element movable transversely of and in front of said plungers, a rotatable cam block engaging said element, and mechanism for rotating said block.

4. A burglar alarm comprising detonating elements including a plurality of retractable plungers provided with firing pins, and means controlling said plungers adapted to successively release the same consisting of a pivoted element movable transversely of and in front of said plungers, a rotatable cam block engaging a free end of said element, mechanism for rotating said block and electrically controlled devices adapted to release said mechanism.

5. A burglar alarm comprising detonating elements including a plurality of retractable plungers provided with firing pins, and means controlling said plungers adapted to successively release the same consisting of a blade pivoted at one end and movable

transversely of and in front of said plungers, a rotatable cam block engaging a free end of said blade, a clockwork for rotating said block, and electrically controlled devices adapted to release said clockwork.

6. A burglar alarm comprising detonating elements including a plurality of retractable plungers provided with firing pins, and means controlling said plungers adapted to successively release the same consisting of a blade pivoted at one end and movable transversely of and in front of said plungers, a rotatable cam block engaging a free end of said blade, a clockwork for rotating said block, and including an escapement, a lever controlling said escapement, a solenoid, and a reciprocable core therefor that is normally in the path of and against which said lever rests and which is adapted to release said lever when said solenoid is energized.

7. A burglar alarm comprising a suitable cabinet one wall whereof is provided with an opening, a closure for said opening, alarm devices within said cabinet, a lock for said closure, and devices adapted to simultaneously start said alarm and release said lock.

8. A burglar alarm comprising a suitable cabinet one wall whereof is provided with an opening, a closure for said opening, alarm devices within said cabinet, a lock for said closure, means for actuating said alarm devices, devices for locking said actuating means, and mechanism for simultaneously starting said alarm devices and releasing said lock.

9. A burglar alarm comprising a cabinet, a pivoted bottom, a latch for retaining said bottom in closed position, a solenoid adapted to retract said latch when said latch is relieved of the weight of said pivoted bottom, alarm mechanism mounted upon said pivoted bottom comprising a chambered bar adapted to receive cartridges in its chambers, firing pins disposed opposite the central portion of said chambers, a lever pivoted to swing into the path of said firing pins, a clockwork alarm mechanism, a member carried upon one of the spindles thereof adapted to move said lever, a solenoid controlling the escapement of said clockwork alarm mechanism, a spring-actuated lever for independently operating the latch mechanism, and a trigger operable by the discharge mechanism for releasing said last-mentioned lever.

Signed at Chicago, county of Cook and State of Illinois, this 21st day of September, 1915.

GEORGE E. YEAGER.
